UNITED STATES PATENT OFFICE.

WILLIAM H. COLE, OF NEWARK, NEW JERSEY.

NON-RESONANT PHONOGRAPH-CABINET.

1,398,626.

Specification of Letters Patent. Patented Nov. 29, 1921.

Application filed May 6, 1920. Serial No. 379,242.

To all whom it may concern:

Be it known that I, WILLIAM H. COLE, a citizen of the United States, residing at Newark, in the count of Essex and State of New Jersey, have invented a new and useful Non-Resonant Phonograph-Cabinet, of which the following is a specification.

The principal object of the present invention is to provide a cabinet incapable of sympathetic sound vibration and yet consisting externally of solid metal and presenting the beautiful appearance and other advantages of design and finish of that material. Other objects of the invention are to avoid joints, to provide sufficient weight and solidity, and to have control of the density of the metal. Additional objects of the invention will appear from the following description at the end of which the invention will be claimed.

In the accompanying drawings I have illustrated one embodiment of the invention and in those drawings—

Figure 1, is an elevational view, and Fig. 2, is a detail section.

The talking machine cabinet shown in the drawings is incapable of sympathetic sound vibration and is composed of a unitary exterior structure of electrolytically deposited metal 1, of any required density or porosity, and of a unitary interior structure 2, of cement material having no fundamental tone and upon which the metal is electrolytically deposited, constituting in effect a unitary laminated structure. Since the cabinet is incapable of sympathetic sound vibration, it in no way mars or detracts from the vibrations or tonal qualities of the reproduction, yet externally it consists of solid metal capable of great beauty of design and finish.

The interior structure 2, may consist of cement, plaster of Paris, papier mâché and the like, because these are examples of cement material having no fundamental tone, or in other words, they are incapable of sympathetic resonance, but in the described association with metal, electrolytically deposited

upon them, they oppose and prevent its sympathetic resonance, making the cabinet as a whole incapable of sympathetic sound vibrations. In the matter of design there are advantages because elaborate designs even in high relief can be readily etched, as with muriatic acid, or otherwise produced, upon the structure 2, and these designs are readily reproduced in the metal structure 1, by coating the structure 2, with suitable material, as graphite, and then electro-depositing the metal structure upon it. In the electro-depositing operation the density or porosity of the metal can be controlled by varying the rate of deposition. Excellent results have been attained by at first depositing the metal slowly thereby obtaining a dense structure, and thereafter depositing the metal more rapidly thereby obtaining a more porous structure. If the designs are undercut, or in fact whatever their configuration may be, the metal structure 1, conforms to them. The structure 2, being of moldable material, can be readily made in one piece and without joints. 3, is sound reproducing mechanism arranged within the cabinet, and 4, is a sound exit which may well be the only opening in the composite laminated wall of the cabinet. The described cabinet is of sufficient weight and solidity to afford a proper foundation for the reproducing mechanism.

In the use of the described cabinet and reproducing mechanism the reproduction is much better than with cabinets having sympathetic resonance, such as wooden cabinets, and the appearance, finish and reproduction are much better than with cabinets of reed, rattan and the like; in fact the advantages of metal are present and its disadvantages are absent.

I claim:

A phonograph cabinet composed externally of metal and internally of cement plaster upon which the metal is deposited and which is a unitary structure possessed of weight and solidity.

WILLIAM H. COLE.
